(57) **CLAIM**

The ornamental design for a high-pressure cleaner, as shown and described.

DESCRIPTION

FIG. 1 is a front perspective view of a high-pressure cleaner in accordance with our new design;

FIG. 2 is a rear perspective view of the high-pressure cleaner in accordance with our new design;

FIG. 3 is a front elevational view of the high-pressure cleaner in accordance with our new design;

FIG. 4 is a rear elevational view of the high-pressure cleaner in accordance with our new design;

FIG. 5 is a top plan view of the high-pressure cleaner in accordance with our new design;

FIG. 6 is a bottom plan view of the high-pressure cleaner in accordance with our new design;

FIG. 7 is a right side elevational view of the high-pressure cleaner in accordance with our new design;

FIG. 8 is a left side elevational view of the high-pressure cleaner in accordance with our new design; and,

FIG. 9 is a front perspective view showing a state in which a hose and an attachment are attached to the high-pressure cleaner in accordance with our new design.

The broken line showing of environmental structures in the drawings forms no part of the claimed design.

1 Claim, 9 Drawing Sheets
